UNITED STATES PATENT OFFICE.

ELISHA E. LEE, OF CAMBRIDGE, NEW YORK.

IMPROVED COMPOSITION FOR SOAP.

Specification forming part of Letters Patent No. **38,685**, dated May 26, 1863.

To all whom it may concern:

Be it known that I, ELISHA E. LEE, of Cambridge, Washington county, State of New York, have invented a new and useful combination of materials or composition of matter, forming a new and valuable soap; and I declare the following specification to be the mode of compounding or manufacturing the same.

Take of the following well-known articles of commerce, five pounds of bleaching compound, two pounds of fuller's earth, one pound of boiled potatoes, six ounces of Indian meal, one table-spoonful of high-wines, half a table-spoonful of spirits of turpentine, one ounce of alum, and

three-eighths of a pound of sal-soda. Mix them thoroughly with one gallon of water, and the product will be a valuable article of soap for family use.

What I claim as my invention, and desire to secure by Letters Patent, is—

The combination of materials set forth in the above specification, forming a new and valuable soap.

ELISHA E. LEE.
